UNITED STATES PATENT OFFICE.

AUGUSTINE DAVIS, OF CHICAGO, ILLINOIS, AND PARIS L. DAVIS, OF MARQUETTE, MICHIGAN.

ACETYLENE-GAS GENERATOR.

SPECIFICATION forming part of Letters Patent No. 705,739, dated July 29, 1902.

Application filed April 16, 1900. Serial No. 13,101. (No model.)

To all whom it may concern:

Be it known that we, AUGUSTINE DAVIS, of Chicago, in the county of Cook and State of Illinois, and PARIS L. DAVIS, of Marquette, 5 in the county of Marquette and State of Michigan, have invented certain new and useful Improvements in Acetylene-Gas Generators, of which the following is a specification.

This invention relates to acetylene-gas generators in which the carbid of calcium is fed to the water, and has for its object to provide feeding mechanism which shall be simple in construction and certain in operation and by means of which uniformity of gas-pressure 15 may be maintained and the carbid fed automatically in very small quantities at frequent intervals, thereby reducing the agitation of the water and obtaining a superior dispersion of heat and purification of gas.

20 A further object of our invention is to insure uniformity of gas-pressure during the feeding operation.

Another object of our invention is to prevent choking of the generating-chamber by 25 residuum or dust accumulations and to obviate the coating of the carbid when delivered by the sludge, thereby preventing local overheating.

Our invention also has for its object the 30 construction of the feeding mechanism in such a way that the generating-chamber, carbid-receptacle, and feeding mechanism are readily accessible for inspection and repair. Provision is also made for approximately indicating the amount of unconsumed material 35 in the receptacle.

To these and other ends our invention consists in certain novel features, which we will now proceed to describe and will then particularly point out in the claims.

In the accompanying drawings, Figure 1 is 40 a vertical sectional view of an apparatus embodying our invention in one form. Fig. 2 is an enlarged sectional view of the carbid-receptacle and its associated parts. Fig. 3 is 45 a plan view of so much of the structure as is shown in Fig. 2. Fig. 4 is a plan section taken on line 4 4 of Fig. 2. Fig. 5 is a plan section taken on line 5 5 of Fig. 2, the lower 50 end of the carbid-chamber being shown in dotted lines. Fig. 6 is a plan section taken

on the line 6 6 of Fig. 1; and Fig. 7 is a plan section of the carbid-receptacle, illustrating the contour of the edges of the baffle-plates.

In the said drawings, 1 indicates the generating-chamber, having a cylindrical body 2, provided at its upper end with a duplicate inner wall 3, thus forming between the two walls an annular space 4, which is filled with 60 water to form a sealing-chamber. The generating-chamber is closed at the top by means of a cap or bell, designated as a whole by 5 and comprising a cylindrical body 6, which fits within the space 4, and a top 7, which in 65 the preferred form of construction serves to support the motor of the feeding mechanism, the cap 5 thus forming, in combination with the water contained in the annular space 4, a water seal.

70 The carbid-receptacle is indicated at 8 and comprises a cylindrical body open at the top and a conical or hopper bottom 9, provided with a contracted delivery-mouth 10. This carbid-receptacle fits within the mouth of the 75 generating-chamber and is provided near its upper end with a screen 11, by means of which the entrance of lumps of carbid greater than the predetermined size into the receptacle is prevented.

80 Mounted centrally within the receptacle 8 is a vertical shaft 12, which has its bearings in transverse supporting-pieces 13 and is provided at its upper end with a coupling member 14, by means of which it may be connected 85 with a motor. This shaft extends down through the discharge-mouth 10 of the receptacle and is provided, at a distance below the same considerably greater than the size of the largest lump of carbid which can be admitted 90 in the receptacle through the screen 11, with a horizontal feed-plate 15, preferably round or disk-like in form and rotating along with the shaft 12. The location of this feed-plate is such that as the carbid passes out of the 95 discharge-mouth of the receptacle it falls upon said feed-plate, and when said feed-plate is rotated it carries around with it the carbid lying upon it, with a circular motion in a plane at right angles to the direction of feed, 100 which is vertical. This movement results in a centrifugal action, which tends to cause the

carbid lying on the feed-plate to move outward toward the edge of the same, it being eventually discharged over the edge of said plate. The action is more in the nature of a 5 drawing of the carbid from underneath the superjacent mass than one of pressing the carbid downward from above, and there results therefrom a free discharge of the carbid, with a minimum tendency to clog at the 10 discharge-mouth of the receptacle.

In conjunction with the rotating feed-plate 15 we employ one or more non-rotating sweeps or scraper-blades 16, arranged obliquely with reference to the radius of the 15 disk 15, and consequently at an angle to the path of motion of the surface of the disk. These sweeps are located immediately above the upper surface of the feed-plate and at a 20 right angle, or approximately so, to the plane thereof. In the present instance we have shown four of these sweeps, the same being carried by a ring or annulus 17, suspended by chains or other flexible connections 18 from the bottom of the carbid-receptacle in such a 25 manner that the sweeps are not rigidly held, but are free to yield to a limited extent, and thus prevent clogging and excessive resistance to the action of the motor. In the particular construction shown the ring or annulus 30 17 and sweeps 16 are made in one piece by cutting out the sweeps along their front and top edges and bending their free ends inward toward the shaft 12, the cut-away portions forming openings for the discharge of 35 the carbid from the feed-plate. Obviously the sweeps may be otherwise constructed and their number may be varied. It will be observed that the relation between the sweeps is such that as the carbid moves outward between 40 the sweeps the space through which it passes is one of constantly-increasing width, so that clogging is avoided. The employment of these sweeps in conjunction with the rotating feeding-plate results in a more positive 45 delivery of the carbid at the edge of the plate and insures a more uniform feed.

Motion is imparted to the shaft 12 and feed-plate 15 by means of a motor, which is preferably mounted on top of the cap or cover 5. 50 As shown, the motor is carried by a frame consisting of a bottom plate 19 and a top plate 20, united by connecting-pieces 21 and supported by brackets 22 on the top 7. The motor comprises a spring 23, attached to the 55 frame 24 and coiled around a shaft 25, to which its other end is attached. The shaft 25 is shaped to receive a winding-key at its upper end and is provided with the usual ratchet-wheel 26, with which engages a detent-pawl 60 27, mounted on a gear-wheel 28, which meshes with a pinion 29 on a central shaft 30. The shaft 30 is in line with the shaft 12 when the apparatus is assembled, and its lower end is provided with a coupling member 31, adapted 65 to engage with the coupling member 14 of the shaft 12. As shown, the member 14 is provided with a plurality of upwardly-extend-

ed arms and the member 31 with a transverse pin, so that the two members may be separated or engaged by a direct movement from 70 or toward each other in the axial line of the shafts. The motor is provided with a fly 32, connected with the main shaft 30 by means of an ordinary clockwork speed-train, including a fly-shaft 33, and serving to regulate 75 the speed of the motor in a well-known manner. The motor is normally held stationary by means of a brake which presses against the fly-shaft 33, the arrangement of gearing being such that a very slight pressure on said shaft will overcome the strength of the spring and arrest the motion of the motor. In the present instance I have shown this brake as consisting of a horizontal bar 34, sliding in guides 35 and provided with a slot 36, through which the upper end of the fly-shaft 33 passes. One end wall of this slot is normally pressed against the shaft 33 by means of a light spring 37, one end of which is secured to the casing 38, which incloses the 90 motor, while its other end passes through an aperture in the slide-bar 34. The motor-brake by means of which the motor is stopped and started is controlled by the bell of the gas-holder through any suitable connecting 95 mechanism, that which we prefer for the purpose being shown and consisting of a rock-shaft 39, having an arm 40, which engages the end of the slide-bar 34, and a second arm 41, preferably provided with a spring-coil 42 to 100 give it a yielding action, its extremity being connected by a chain or other flexible connection 43 with the bell of the gas-holder hereinafter described.

44 indicates a vessel the upper portion of 105 which forms a gas-holder, being provided with a bell 45 and the usual water seal for this purpose, while the lower portion forms a water-chamber and sludge-receptacle 46, provided with a conical bottom 47, having a downwardly-inclined lateral outlet 48, closed by a suitable valve 49. The body 2 of the generating-chamber is connected with the vessel 44, at one side thereof, immediately above the discharge-outlet 48 of the sludge-receptacle 110 46. The vessel 44 is provided with an opening 50, through which connection is established between the chambers 1 and 46, and the body 2 is provided with an inclined bottom 51, which forms an extension of the inclined bottom 47 of the chamber 46 and which, together with the adjacent portion of said bottom 47, forms a single continuous incline from the generating-chamber to the sludge-outlet 48, as shown more particularly in Figs. 1 and 6 115 120 125 of the drawings. The normal water-level in the chambers 1 and 46 is about the top of the opening 50, and the chamber 46 is separated from the gas-holder by a diaphragm or partition 52. The gas as it is generated passes up 130 through a suitable conduit, as 53, into the bell 45.

We provide means for preventing the gas-pressure from imparting vertical movement

to the cap or cover 5 and the motor carried thereby, and for this purpose we prefer to employ an arm 54, which may be swung over the top of the motor to act as a stop to limit the upward movement of the parts or which may be swung to one side, so as to permit their removal. In practice we have shown this arm 54 as constituting the handle of a valve-stem 55 of a valve 56, controlling a vent-
10 pipe 57, by means of which air may be permitted to escape from or enter the generating-chamber 1 during the insertion and removal of the cover.

In order to prevent clogging within the car-
15 bid-receptacle by the "bridging" of the pieces of carbid therein, we employ baffle-plates in the form of downwardly-inclined conical plates which tend to deflect the carbid as it passes downward and prevent the interlocking or
20 wedging of the lumps together. The particular arrangement of these plates which we prefer is that shown in Fig. 2 of the drawings, in which an upper baffle-plate 58 is employed in the form of an annular inclined plate se-
25 cured at its outer edges to the body of the receptacle and having a central opening in conjunction with a lower plate 59 in the form of a cone closed at the top and extending outward toward but not to the wall of the recep-
30 tacle. The body of the upper baffle-plate is downwardly convergent, while the body of the lower baffle-plate is downwardly divergent. We prefer to make the lower edges of the baffle-
35 plates not truly circular in form, but of a form which is of greater diameter in one direction than in another, as indicated at Fig. 7. We also prefer to so arrange these plates that their longest diameters are not coincident, but at an angle to each other. The desirability of this
40 arrangement arises from the fact that it pre-
vents the lumps of carbid from forming into a circle which acts as an arch to hold the mass above it, and thereby prevent its feed-
45 ing downward. While we prefer the arrange-
50 ment shown in Fig. 2, we find that the arrange-
55 ment shown in Fig. 1 of the drawings, in which both of the plates are downwardly divergent, produces good results, and we may also dis-
50 pense with the connection of the upper plate to the wall of the receptacle, as shown in Fig.
1. As a further means for preventing clog-
60 ging we may flatten or somewhat distort the portion of the shaft 12 which lies within the discharge-throat 10 of the receptacle, as shown at 60 in Fig. 2, so as to cause it to tend to stir the carbid which occupies the throat. In order to provide means for determining the amount of material remaining in the carbid-
65 receptacle without removing the same, we have provided an indicating apparatus consisting of a suitably-divided indicator disk or scale 61, around which travels an indicating-finger 62, mounted on a shaft 63, which carries a gear-wheel 64, which meshes with a pinion 65 on the spring-shaft 25. As the amount of carbid discharged at each revolution of the feed-plate is practically the same,

this indicating mechanism will at all times show approximately how much unused material remains available, without the necessity of opening up the generator to inspect the interior thereof.

The operation of the apparatus is as fol-
lows: An initial charge of carbid having been fed into the water of the generating-chamber, 75 the gas generated will pass into the bell 45 and will lift the bell, so as to remove its weight from the chains 43, thereby causing the bar 34 to be pressed by the spring 37 against the fly-shaft 33, thus stopping the 80 motor and arresting the feed. As soon as the supply of gas in the bell has been reduced to a sufficient extent for the purpose, the weight of the bell will, through the connecting mech-
anism provided for that purpose, withdraw 85 the bar 34 from contact with the fly-shaft and permit the motor to operate, whereupon another charge of carbid will be fed into the water and the bell will again rise, permitting the spring 37 to again arrest the motor. The 90 arrangement is such that the feed occurs with great frequency and the carbid is fed into the water in very small charges, so that the violent ebullition and the dashing up of spray, steam, and dust, which results from 95 the dropping of a large amount of carbid in the water, is avoided, and the generating-chamber is prevented from being befouled and clogged by the same. At the same time the gas is generated in smaller quantities at 100 one time and more uniformly, thereby allowing greater opportunity for heat dispersion, condensation, and purification. We have found that by feeding the carbid in small amounts by the feeding mechanism devised 105 by us carbid in the form of dust or powder may be employed with practical success. The comparatively small amount of carbid upon the feed-disk is all that is exposed to the moisture of the generating-chamber, and the after generation is therefore reduced to 110 an amount easily contained by the gas-holder, thereby preventing loss. The feeding mech-
anism is operated by an independent motor, and the weight of the bell is relied upon sim- 115 plly to release the brake against the action of its comparatively-feeble operating-spring. It results from this construction that the con-
trolling of the feed from the bell does not subtract to any appreciable extent from the 120 weight of the bell of the gas-holder and the pressure upon the gas is practically constant. Moreover, the independent motor insures gas generation until the bell rises, which rising cannot occur until there is an excess of gas 125 above the consumption. The feeding de-
vices proper are organized to prevent clog-
ging and operate more by the withdrawal of the lower portion of the carbid than by any pressure from above, so that packing or 130 bridging of the carbid is prevented and cer-
tainty of feeding is obtained. The remova-
bility of the entire feeding mechanism, both as to the motor and as to the feeding devices

proper, permits constant and ready inspection and renders these devices easily accessible for repairs, while at the same time it permits immediate substitution of duplicate apparatus in case of injury. The arrangement of the generating-chamber proper at one side of but in immediate communication with the comparatively large main water-and-sludge chamber insures a proper circulation and free intermingling of the water in the two chambers, while the arrangement of the inclined bottom of the generating-chamber as a direct extension of the inclined bottom of the sludge-chamber and immediately in line with the sludge-discharge pocket prevents the accumulation of sludge at the bottom of the generating-chamber, immediately below the point where the carbid enters the water. It results from this that the freshly-fed pieces of carbid are not discharged into a mass of sludge, which might envelop or coat the particles, and thereby cause them to become overheated before complete hydration could occur. This prevention of local overheating insures a better quality of gas.

We do not wish to be understood as limiting ourselves to the precise details of construction shown and described as constituting one embodiment of our invention, since it is obvious that various modifications in the structure may be made without departing from the principle of our invention.

We claim—

1. The combination with a stationary casing having an open upper end and a peripheral annular water-chamber, of a carbid-receptacle removably seated in said stationary casing, said receptacle having an open discharge-mouth at its lower end, a cap or bell 40 the top whereof constitutes a cover for the carbid-receptacle and the depending walls whereof enter the annular water-chamber of the casing to constitute therewith a water seal, a horizontal feed-plate located below the 45 mouth of the carbid-receptacle, a vertical driving-shaft extending therefrom upwardly through said receptacle and the top of said cap, and means for imparting a rotary motion to said feed-plate through said shaft, substantially as described.

2. The combination with a stationary casing having an open upper end and a peripheral annular water-chamber, of a carbid-receptacle removably seated in said stationary casing, said receptacle having an open discharge-mouth at its lower end, a cap or bell 55 the top whereof constitutes a cover for the carbid-receptacle and the depending walls whereof enter the annular water-chamber of the casing to constitute therewith a water seal, a horizontal feed-plate located below the mouth of the carbid-receptacle, a vertical driving-shaft extending therefrom upwardly through said receptacle and the top of said 60 cap, a coupling connecting separated ends of said shaft within said carbid-receptacle, and means for imparting a rotary motion to said

feed-plate through said shaft and its coupling member, substantially as described.

3. The combination, with a carbid-receptacle having an open mouth at its lower end, of a horizontal feed-plate located below said mouth, a universally-yieldable sweep or scraper flexibly suspended over said feed-plate, and means for rotating said feed-plate, substantially as described.

4. The combination, with a carbid-receptacle having an open discharge-mouth at its lower end, of a horizontal feed-plate located below said mouth, a plurality of universally-yieldable sweeps or scrapers flexibly suspended over said feed-plate, and means for rotating said feed-plate, substantially as described.

5. The combination, with a carbid-receptacle having an open discharge-mouth in its lower portion, of a horizontal feed-plate located below said mouth, means for rotating said feed-plate, and an annulus flexibly suspended over said feed-plate and provided with one or more sweeps or scrapers, extending diagonally over said plate, substantially as described.

6. The combination, with a vertical carbid-receptacle having an open discharge-mouth in its lower portion, of conical baffle-plates located within said receptacle, said plates being oval in peripheral contour and having their longest diameter disposed at an angle to each other.

7. The combination, with a carbid-receptacle having a contracted open discharge-mouth at its lower end, and a horizontal rotary feed-plate located below said mouth, of conical baffle-plates within the carbid-receptacle, said plates being oval in peripheral contour and asymmetrical relatively to each other and having their longer diameters arranged at an angle to each other, substantially as described.

8. The combination, with a carbid-receptacle having a contracted open mouth in its lower end, of a horizontal feed-plate located below said mouth, and a vertical shaft carrying said plate, extending upward through the receptacle and having that portion which lies within the discharge-mouth flattened, substantially as described.

9. The combination, with a carbid-receptacle having an open discharge-mouth in its lower end, and a horizontal feed-plate located below said mouth and provided with a vertical shaft extending upwardly through the receptacle, of an independent motor connected with the upper end of said shaft, and means controlled by the variations in volume of the generated gas for stopping and starting said motor, substantially as described.

10. The combination, with a carbid-receptacle having an open discharge-mouth in its lower portion, of a horizontal feed-plate located below said mouth, an independent motor connected with said feed-plate to rotate the same, a brake normally holding said mo-

tor stationary, and means controlled by the variations in volume of the generated gas for releasing said brake, substantially as described.

- 5 11. The combination with an open-topped generating-chamber provided about its periphery with an annular sealing-chamber, of a carbid-receptacle provided with feed devices and removably located within the generating-chamber, a removable cap entering said sealing-chamber and constituting therewith a water seal, the top of said cap resting on and forming a cover for the carbid-receptacle, and an independent motor for the feed devices carried on the top of said cap and removable therewith, substantially as described.
- 10 12. The combination with an open-topped generating-chamber provided about its periphery with an annular sealing-chamber, of a carbid-receptacle provided with feed de-

vices and removably located within the generating-chamber, a removable cap entering said sealing-chamber and constituting therewith a water seal, the top of said cap resting on and forming a cover for the carbid-receptacle, an independent motor for the feed devices carried on the top of said cap and removable therewith, and means for locking said cap against vertical movement, substantially as described. ²⁵
